COMBINED SIGN AND DISPLAY STAND FOR TIRES

Guy L. Huey and Elliott J. Kies, Massillon, Ohio, assignors to The Massillon-Cleveland-Akron Sign Company, Massillon, Ohio, a corporation of Ohio

Filed May 19, 1964, Ser. No. 80,047

Term of patent 14 years

(Cl. D80—9)

Fig. 4

Fig. 2

Fig. 3

Fig. 5

FIGURE 1 is a perspective view of a combined sign and display stand for tires showing our new design;

FIG. 2 is a front elevational view thereof;

FIG. 3 is a side elevational view thereof;

FIG. 4 is a top plan view thereof;

FIG. 5 is a bottom plan view thereof; and

FIG. 6 is a vertical sectional view taken on the line 6—6 of FIG. 2.

The broken lines showing of tires in FIG. 1 are for illustrative purposes only.

We claim:

The ornamental design for a combined sign and display stand for tires, substantially as shown and described.
